UNITED STATES PATENT OFFICE.

CLARENCE N. SCOTT, OF BUFFALO, NEW YORK, ASSIGNOR TO INTERNATIONAL STEAM PUMP COMPANY, OF NEW YORK, N. Y., A CORPORATION OF NEW JERSEY.

ADMISSION-VALVE FOR GAS-ENGINES.

1,117,258.

Specification of Letters Patent.

Patented Nov. 17, 1914.

Original application filed January 23, 1905, Serial No. 242,280. Divided and this application filed December 14, 1907. Serial No. 406,517.

To all whom it may concern:

Be it known that I, CLARENCE N. SCOTT, a subject of the King of Great Britain, residing at Buffalo, county of Erie, and State 5 of New York, have invented certain new and useful Improvements in Admission-Valves for Gas-Engines, fully described and represented in the following specification and the accompanying drawings, forming a 10 part of the same.

This invention relates to inlet valve mechanism for internal combustion engines, the object being to provide an efficient and reliable valve mechanism employing a regulating or cut-off valve separate from the distributing valve.

For a full understanding of the invention a detailed description of a construction embodying all the features of the same in the 20 preferred form will now be given in connection with the accompanying drawings forming a part of this specification, and the features forming the invention then specifically pointed out in the claims.

25 In the drawings—Figure 1 is a vertical central section of the valve casing and valve mechanism. Fig. 2 is a vertical central section through the valve casing taken at right angles to Fig. 1. Figs. 3, 4, 5 and 6 are horizontal sections on, respectively, the lines 30 3, 4, 5 and 6 of Fig. 1. Figs. 7 and 8 are detail sections of the valve casing and valves on the same line as Fig. 1, showing the valves in different positions.

35 Referring to the drawings, A is the explosion chamber or end of the engine cylinder, B the valve casing mounted thereon and C a bracket on the top of the valve casing forming a support for the valve mechanism.

40 The casing B is provided with air inlet 10 and gas inlet 11, the air and gas inlets communicating with the interior of the valve through their respective air and gas inlet ports 1, 2 in inner casing 12, the air ports 45 being shown as extending through a large portion of the inner casing 12 and the gas ports through a small portion, this depending upon the character of the gas to be used.

The gas ports are preferably small, as 50 shown, so as to divide the gas into small jets and secure a thorough mixing of the air and gas, and to provide for regulating the quality of the mixture by a small adjustment of the valve. The inlet valve *a* seats

upon a seat 3 on the bottom of the casing, 55 and is carried by stem 13, on which is secured rigidly with inlet valve *a* the cylindrical distributing valve *b* on arms 14 on the valve stem 13. The distributing valve *b* is provided with air inlet ports 4 and gas 60 inlet ports 5 arranged to register with the air and gas ports 1, 2 in inner casing 12. A cylindrical regulating or cut off valve *c* is mounted inside the distributing valve *b*, this valve *c* being carried by arms 15 on 65 sleeve 16 mounted to slide on valve stem 13, its lower edge being seated on shoulder 6 on valve *b*, and the lower end of the sleeve in seat 7 on the valve stem 13 when the valves are closed, as shown in Figs. 1 and 2. The 70 seat 7 preferably forms a dash pot to cushion the cut off valve at the end of its downward movement, and may be provided with an adjustable air escape valve, if desired. A back firing relief valve is prefer- 75 ably used to allow the products of combustion in the valves to pass out into the air pipe and thus relieve the pressure in the valves, an annular valve *d* spring seated by spring 17 being shown for this purpose, this 80 valve opening the interior of the valves to the air inlet through ports 8.

The valve stem 13 carrying valves *a*, *b* is adjustably connected at its upper end to the cross head 18 guided in the upper end of the 85 bracket C and is connected to the end of the valve operating lever 19 by block 20 in which the lever 19 is pivoted, this block being mounted in the cross head so as to permit slight rotary movement of the latter 90 for rotary adjustment of the valve *b*, the lever 19 being operated by cam rod 21 from cam 22 on the cam shaft 23 to open the valve and returned to close the valve by spring 24, which is a tension spring ex- 95 tended by the operation of cam 22 in opening the valve and preferably made adjustable as shown. The cross head 18 is shown as provided with a square end 25 extending above the bracket C for application of a 100 wrench to rotate the valve stem.

The sleeve 16 carrying the regulating or cut off valve *c* is mounted to slide vertically in a stationary sleeve 26, and is spring pressed downward by spring 27 on the valve stem 13, which spring is inclosed by the sleeve 16, bears at its lower end against the sleeve 16, bears at its lower end against the sleeve 16, and has at its upper end an adjust- 105

able bearing 28 on the valve stem 13. The sleeve 16 with valve *c* is held in its upper position against the pressure of spring 27 by pivoted catch *e* pressed against the sleeve 16 by spring 9, and withdrawn against the pressure of spring 9 at the proper time to release the sleeve 16 for the closing of the regulating or cut off valve *c* by cam lever 29 operated by cam 30 on governor controlled cam shaft 31, this shaft 31 being controlled by any suitable governor which advances or retards the rotation of the shaft, so as to cause the regulating or cut off valve *c* to drop earlier or later in the stroke, according to the speed of the engine.

A suitable governor and its connections to shaft 31 for controlling the continuous rotation of the latter so as to withdraw catch *e* at the proper time, are shown in my Letters Patent No. 898,271.

The operation of the construction is as follows:—The inlet valve *a* is opened by cam 22 acting through cam rod 21, lever 19 and valve stem 13, and the distributing valve *b* is at the same time moved downward so that its air and gas ports 4, 5 pass the lower edge of the inner casing 12 and open air and gas ports 1, 2, to the interior of the valve and thus admit to the explosion chamber or cylinder through the open inlet valve *a* the charge of air and gas mixed within the valve, the parts then being in the position shown in Fig. 7. Air and gas are thus admitted through the distributing valve *b* until the rotation of the governor controlled shaft 31 withdraws the catch *e* by cam 30 and cam rod 29 against the pressure of spring 9, so as to release the sleeve 16, when the spring 27 which has been put under tension by the downward movement of the valve stem 13, throws the sleeve 16 and regulating or cut off valve *c* downward to close the air and gas inlet ports, as shown in Fig. 8, so that no air or gas is admitted during the remainder of the suction stroke. The inlet valve *a* and distributing valve *b* are now raised to close these valves by the spring 24 acting through lever 19 and valve stem 13, and the regulating or cut off valve *c* is carried upward by the valves *a*, *b*, and all the parts thus returned to normal position, as shown in Figs. 1 and 2. On ignition, the pressure produced by the firing of the gases within the valves *b*, *c* will be relieved through the opening of the automatic relief valve *d* and the burnt gases thus blown out to the air pipe.

The valve mechanism may be used without provision for adjusting the relative amounts of gas and air, the air and valve ports being suitably proportioned, but it is preferable that some means be provided for adjusting the relative amounts of air and gas, in accordance with the quality of the gas used or to vary the quality of the mix-

ture. In the construction shown, this result is secured by the rotation of the valve *b* by the head 25, as previously described, this slight rotation being permitted by the connection between the cross head 18 and the lever block 20. The gas ports 5 in the valve may thus be adjusted relatively to the gas ports 2 in the inner casing 12, so as to regulate as desired the amount of gas admitted. The air ports may be formed so that the amount of air admitted is adjusted simultaneously with the amount of gas, if desired, or the air supply may be substantially uniform.

The subject-matter claimed herein is shown and described, but not claimed, in my application Serial No. 242,280, filed January 23, 1905, of which the present application is a division.

What is claimed is:

1. In an internal combustion engine, the combination with an inlet valve, of a distributing valve controlling the air and gas ports, and a governor controlled regulating valve separate from the distributing valve and arranged to cut off the admission through the distributing valve at varying times with relation to the closing of the inlet valve in accordance with the operation of the engine.

2. In an internal combustion engine, the combination with a cylindrical distributing valve controlling the air and gas ports, of a cylindrical governor controlled regulating valve separate from the distributing valve and moving parallel with the distributing valve for varying the length of time during which the ports are open, in accordance with the operation of the engine.

3. In an internal combustion engine, the combination with an inlet valve, of a distributing valve in line with the inlet valve controlling the air and gas ports, means for actuating the inlet and distributing valves for admission, and a governor controlled regulating valve separate from the distributing valve and arranged to cut off the admission through the distributing valve at varying times with relation to the closing of the inlet valve in accordance with the operation of the engine.

4. In an internal combustion engine, the combination with an inlet valve and its valve stem, of a cylindrical distributing valve carried by the valve stem and controlling the air and gas ports, a regulating valve separate from the distributing valve and moving longitudinally of the valve stem, and means for moving the regulating valve independently of the distributing valve to vary the time during which the ports are open.

5. In an internal combustion engine, the combination with an inlet valve and its valve stem, of a cylindrical distributing valve carried by the valve stem, a cylindrical

regulating valve spring actuated to close the ports and returned by the valve stem in the closing movement of the inlet valve, and governor controlled means for releasing the regulating valve for the spring actuated movement.

6. In an internal combustion engine, the combination with a cylindrical distributing valve controlling the air and gas ports, of a regulating valve separate from the distributing valve and acting to cut off the admission of air and gas through the distributing valve, a spring for actuating the regulating valve, and governor controlled means for varying the time of cut off by the regulating valve in accordance with the operation of the engine.

7. In an internal combustion engine, the combination with a cylindrical distributing valve, of a regulating valve separate from the distributing valve and acting to cut off the admission of air and gas through the distributing valve, a spring for actuating the regulating valve, a catch for holding the regulating valve in position and governor controlled means for releasing the catch.

8. The combination with the inlet valve *a*, of cylindrical distributing valve *b*, valve casing *B* having air and gas ports controlled by the distributing valve, and a governor controlled cylindrical regulating valve *c* arranged to close the air and gas ports independently of the distributing valve and at varying times with relation to the closing of the inlet valve, substantially as described.

9. The combination with the inlet valve *a*, of cylindrical distributing valve *b*, valve casing *B* having air and gas ports controlled by the distributing valve, governor con-

trolled cylindrical regulating valve *c* arranged to close the air and gas ports independently of the distributing valve, a spring for actuating the valve *c*, and a governor controlled catch for holding and releasing the valve *c*, substantially as described.

10. The combination, with a valve casing having air ports and gas ports, an angularly adjustable longitudinally movable distributing valve provided with ports arranged to permit the passage of air and gas from the air and gas ports of the casing, and means for moving said distributing valve longitudinally to open and close said air and gas ports, of a governor-tripped quick-acting cut-off valve arranged to cut off the ports of the distributing valve.

11. In an internal combustion engine, the combination, with an inlet valve, means for opening and closing said valve at predetermined points of the engine stroke, and a cut-off valve arranged to control the admission of mixture to the inlet valve, of means coaxial with the cut-off valve and arranged to adjust the proportions of the mixture, means for opening the cut-off valve simultaneously with the inlet valve, and governor-controlled means for closing the cut-off valve at varying times before the closing of the inlet valve in accordance with the operation of the engine.

In testimony whereof, I have hereunto set my hand, in the presence of two subscribing witnesses.

CLARENCE N. SCOTT.
